UNITED STATES PATENT OFFICE.

FELIX E. VALOIS, OF HAVERHILL, MASSACHUSETTS, ASSIGNOR TO HAMEL SHOE MACHINERY COMPANY, OF LYNN, MASSACHUSETTS, A CORPORATION OF MASSACHUSETTS.

WELT-BEATING MACHINE.

1,089,025.

Specification of Letters Patent.

Patented Mar. 3, 1914.

Application filed October 24, 1912. Serial No. 727,512.

To all whom it may concern:

Be it known that I, FELIX E. VALOIS, a citizen of the United States, residing at Haverhill, county of Essex, State of Massachusetts, have invented a certain new and useful Improvement in Welt-Beating Machines, of which the following is a specification, reference being had therein to the accompanying drawings.

10 My invention relates to a welt beating machine intended to operate to separate the outer edge of the welt from the upper of a shoe and press down the welt to cause it to stand at an angle from said upper so that 15 the sole may be more readily secured to said welt.

The object of my invention is to produce an effective mechanical device for the above purpose.

20 It consists in certain novel features of construction and operation, all as herein-after more fully set forth in the following description of a machine embodying my invention, and illustrated in the accompanying 25 drawings forming a part hereof.

The novel features of my invention are pointed out and clearly defined in the claims at the close of the specification.

In the drawings, Figure 1 is a side elevation 30 of a machine embodying my invention showing the periphery of the welt beater in its highest position. Fig. 2 is an end elevation of a machine embodying my invention. Fig. 3 is a detail showing particularly the work support and the welt beater in contact with a welt which is secured to a shoe upper, said welt beater, shoe parts and work support being in section. Fig. 4 is an elevation of a modified form 40 of machine comprising two welt beaters and showing means for mounting and operating the same. Fig. 5 is a detail view illustrative of the means for adjusting the work-support.

45 Having reference to the drawings,—the frame of the machine is shown at A and is of common form and ordinary construction. Mounted in the frame is a shaft B having thereon a pulley C, for driving which any suitable means may be employed. On the free or outer end of the shaft B the welt beating wheel or member D is mounted, as shown in Fig. 1. This wheel comprises an eccentric 1, (see Fig. 3) and a rim or beating surface 2. The rim 2 has a continuous

or uninterrupted periphery or tread, and said rim closely fits the circular eccentric 1. Said rim has an inwardly extending flange 3 and an inwardly extending flange 4, the latter being detachably secured to the rim by means of bolts 5. The rim 2 is thus secured to the eccentric and at the same time may be rotated with reference to it. While other equivalent structures might possibly be used, I prefer to employ a slidable rim to do away with the friction between the rotating beater and the material upon which it operates. The welt 6 of the upper 7 of a shoe is placed upon the work support 8, as shown in Fig. 3. This work support 70 comprises two parts, the upper part or anvil 10 being secured to the lower part or arm 9 by means of a pivot pin 11, said pin enabling the anvil to be rotated. The arm portion is pivoted at 12 in the base of the frame A, said arm portion being forked to admit the pivoted block 13 through which the adjustment bolt 14 is screwed. The pivots 141 of the block 13 are received in openings 142 in the forked portion of the 80 arm or lever 9. The adjustment bolt 14 is provided with a set nut 15 by which it may be locked and the work support secured in any position desired. By this means the work support may be tilted, which enables the surface thereof to be placed at any desired angle with reference to the periphery of the beater member. Of course, if desired, any well known kind of support and means of adjustment may be used instead of the 90 one hereinabove described.

The end of the shaft B opposite to that on which the beater member D is mounted rests in a bearing pivoted by the pins 16 in the frame A to allow a vertical oscillation to the shaft. This bearing is an extension of the goose neck 90, the other end of said goose neck being cast integral with the bearing 17 thereby effectively connecting the bearing 17 to the rear of the frame A by means of the pin 16, as is clearly shown in Fig. 1. The shaft B rests near its forward end in the bearing 17, said bearing being rectangular in shape and fitted into a vertical slot 18, as shown in Fig. 2. The bearing may thus be moved up or down by an adjustable support, which consists of a screw 19 threaded into a bracket 20 fixed to the frame A, said support being locked by the set nut 21. By this means the beater 100

105

110

member may be placed at any height from the work support desired. The bearing is held against the screw support by means of a helical spring 22 which may be adjusted in tension by the set screw 23. Every time the periphery of the rotating member comes in contact with the welt the spring permits a yielding pressure to be brought to bear on said welt, and thus does away with all risk of tearing the same. In other words the free or outer end of the shaft B is adapted to move vertically when the machine is in operation, the rim of the beater member D having a yielding pressure on the 15 welt.

Inasmuch as welts vary materially in width I have found it convenient to adjust the amount of periphery of the beater member to be placed above the work support to 20 take care of a welt of any particular width. To do this I provide in the type of machine shown in Fig. 1 a means of adjusting the shaft B lengthwise of its axis. The collars 24 and 25 are secured to the shaft on each 25 side of the bearing 17 by means of adjustment screws 26 so as to rotate with the shaft. By this means the beater may be secured in any lateral relation to the work support.

30 The machine described above and shown in Fig. 1 is equipped with one beater member only. Fig. 4 shows a modified form of machine where the same principle is applied but which has two beater members instead 35 of one, thus having double the capacity of the other machine. The frame E of the machine, shown in Fig. 4, has mounted thereon in the bearings 27 a shaft F. The shaft is driven by means of the pulley K secured to 40 the center thereof. On each end of said shaft are the beater members G and H, which are of the same principle and design as the one shown in Fig. 1 and hereinabove described. They are mounted conversely, 45 that is, so that the periphery of one beater is at the lowest point when the periphery of the other beater is at the highest point, which is plain from Fig. 4. The bearings 27 are placed in the frame in the same 50 manner as bearing 17, shown in Fig. 1, each of said bearings being supported by an adjustment screw 28 and each having pressure brought to bear upon its upper surface by the helical spring 29, all in the same manner 55 as bearing 17, shown in Fig. 1, and hereinabove described. To prevent slippage of the shaft F in the direction of its axis I provide pins 30 fitted into each bearing 27 and engaging perpendicular slots 31 in the 60 frame E. By this construction the shaft F is permitted to oscillate perpendicularly in the same manner as bearing 17 in the form of machine described above, shown in Fig.

65 1. I prefer to place the beater members conversely for the better working of the

machine. The shaft F is secured in its position, while at the same time it is allowed to rotate, by means of the collars 32 and 33, placed at the outside ends of the bearings 27 and secured to the shaft by means of the 70 set screws 34 and 35. In this machine, as well as in the machine shown in Fig. 1, it is essential that the amount of periphery of the beater members which is over the work support should be increased or diminished 75 as is necessary for the particular width of welt under operation. Inasmuch as the shaft cannot be moved along its axis where there is a beater member on each end thereof, I have provided for an adjustable work 80 support. A plate 36 is secured to the main portion of the work support by any well known means. This plate has therein a slot 37 parallel to the shaft F. Through this slot a bolt 38 extends which secures the 85 plate firmly to the frame of the machine. By loosening this bolt the support may be placed under the periphery of the beater member to any extent required, and thus a welt of any width may be operated upon. 90

It will be found that the constructions hereinabove described act on the material in a peculiar manner, the result being that the material is completely pressed and flattened by passing through the machine once. The 95 welt is stretched on the curves so as to lie flat without necessitating notching the edge of the welt. Furthermore the work is performed with great rapidity.

What I claim is:

1. In a welt beating machine, the combination with a work support having a pivoted anvil part, of a circular rotary beater eccentrically mounted and having a continuous or uninterrupted periphery.

2. In a welt beating machine, the combination with a work support having a pivoted anvil part, of a rotary beater comprising a slidable rim.

3. In a welt beating machine, the combination with a work support, of a vertically movable shaft, and an eccentrically mounted rotary beater located at the outer end of said shaft and comprising a slidable rim.

4. In a welt beating machine, the combination with a work support, of a vertically movable yieldingly mounted shaft, a rotary beater with a slidable rim at the outer end of said shaft, and means for detachably securing said rim.

5. In a welt beating machine, the combination with a work support, of a rotary shaft, and an eccentric beater at the outer end of said shaft and having a slidable rim, said rim being fitted with an inwardly extending flange at one side and a detachably secured inwardly extending flange at the other side.

6. In a welt beating machine, the combination with a work support, of an eccentric

100

105

110

115

120

125

130

rotary beater the rim of which operates upon the work, and a yieldingly mounted shaft at the outer end of which said beater is carried.

5 7. In a welt beating machine, the combination with a work support, of an eccentric beater the rim of which operates upon the work, and a longitudinally adjustable and yieldingly mounted shaft at the outer end 10 of which said beater is carried.

8. In a welt beating machine, the combination of a work support for the shoe to be operated upon, and comprising an anvil member having an edge beneath the beating 15 member, the upper surface of said anvil member being adapted to support the welt

of the shoe with the edge of the anvil in contact with the upper, and a rotary beating member consisting of an eccentric having a slidable rim closely fitting said eccentric and bearing against said edge. 20

9. In a welt beating machine, the combination with a shoe supporting anvil, of a beating member comprising a rotary eccentric having a slidable rim closely fitting said 25 eccentric.

In testimony whereof I affix my signature, in presence of two witnesses.

FELIX E. VALOIS.
